UNITED STATES PATENT OFFICE

HEINRICH STOLZE, OF SCHWANEBECK, GERMANY

BEET-ROOT GATHERING MACHINE

Application filed November 18, 1939, Serial No. 403,097, and in Germany November 23, 1928.

This invention relates to a beet-root gathering machine by means of which first the beet-root tops are cut off, whereupon the beet-roots are loosened by shares and then lifted out of the ground by forkshaped lifters so that they are deposited at the sides of the lifters to be engaged by an oblique rake, along which they roll to the outer side where they are deposited in rows, whereas the beet-root tops also conveyed to the outer side of the machine are deposited in heaps.

In the accompanying drawings an embodiment of the invention is illustrated by way of example.

15 Fig. 1 is a top plan view of the machine.

Fig. 2 is a longitudinal section of the same.

Fig. 3 is a cross section on line 3—3 of Fig. 1.

20 The machine has a fixed front axle 1 on which the front wheels are mounted, steered by means of axle swivels 3 and a steering rod 4 from the driver's seat 5 through the intermediary of a steering wheel or the like. 25 The rear wheel axle is rigid with the rear wheels so that it participates in the turning movements of the same. On the front axle two longitudinal members 8 rest and are rigidly connected to the same, said members carrying in bearings 9 the rear axle 6.

30 The machine is fitted with three rows of knives and lifters. It is adapted to be attached to a tractor at the side of which it runs and with which it is connected in a suitable manner.

35 The three knives 10 for cutting off the beet-root tops are attached to a transverse beam 11 ending in rollers 12 which are movable in guides 13 (Fig. 1). The knives 10 are 40 adjustable in the vertical direction independently of each other and controlled by shoes 14 sliding along the ground and moving ahead of the knives so that they move over the beet-root tops whereby to the knives 45 the correct cutting position is given. The knives cut therefore only so much from the top end of the beet-roots as is necessary to keep together the beet-root top. By adjusting screws 15 the shoes 14 can be adjusted with 50 regard to the knives 10. These knives 10 are

connected to guide rods 16 rigidly connected with the transverse beam 11. The rods 16 end in racks 17 with which spur wheels 18 engage, on the shaft 19 of which a sprocket wheel 20 is keyed, connected by a chain 21 with a sprocket wheel 22 (Fig. 1), the latter being mounted on a bracket 23 and adapted to be rotated from the driver's seat 5 by means of a crank handle 24. The rods 16 are thus raised and lowered, an abutment 25 of the 55 knife shanks 11 bearing against a guide sleeve 26 for the knives so that these knives and the shoes 14 are raised also.

60 The cut off beet-root tops strike either against guide plates 27 (Fig. 1) which guide the same in upward direction, or they drop on to the plate 30 and 29 on which latter they are raised onto the conveyor bands 28, so that the tops can easily be conveyed upwards.

65 The band 28 has transverse bars that push 70 the tops up the plate 29 and throw them onto the conveying device 31.

75 The lower shaft of band 28 is suspended in bearings fixed on the main frame of the machine, which bearings are not shown, as they are regarded as of minor importance. The plate 29 is suspended from the same 80 bearings, and its lower end forms an extension of both the bearings.

85 The small trapezoid in Fig. 2 below sleeve 26 and at the right of the head of the screw 15 forms a sleeve 26'' which receives the screw 15.

85 The same sleeve receives the vertical shank 10' of knife 10.

90 The shoe 14 is rigidly connected to the same sleeve 26'' so that the plate 14 controls the knife. The sleeve 26 is provided with a slot 26' in the front portion of its wall in which the knife bar can yield towards the front when the plate 14 is raised, the rod 16 having also an according slot 16' in order to enable the abutment 25 to swing out towards the rear when the plate 14 is being raised.

95 The plate 30 is hingedly connected at its front end to the rear ends of the plate 14. Moreover the plate 30 is connected at its rear end with the front and lower end of the plate 29.

The plate 29 is connected at its rear end to bearings fixed on the frame 8.

The cut-off tops do not drop onto the conveyor band 28 but onto the plates 30 and 29. The beet-root tops drop from the plate 29 upon a transverse conveying device 31, from which they drop into a box 32 arranged on the side of the machine. In this box 32 a rotatable vane drum 33 is arranged, which is normally locked by a spring-controlled latch 34. When this latch 34 is pulled back by means of a pull rod 35 through the intermediary of a lever 36 in easy access from the driver's seat 5, or by the operation of a pedal lever, the vane loaded with beet-root-tops is released, so that the heap of beet-root-tops resting on said vane drops on the ground. The next following vane comes at the same time to rest on the latch 34 so that the depositing of the beet-root tops in the box 32 is not interrupted. The conveying device 31 is driven from the rear axle by bevel wheels 37 and 38 and sprocket wheels 39 and 40 connected by a chain 41.

The shares 42 (Fig. 2) for loosening the beet-roots and the fork-shaped lifters 43 are fixed the one behind the other on carriers 44, fixed on transverse axles 45 oscillatably mounted on crank pins 46. In order to adjust the distance of the shares 42 from the lifters 43 in accordance with the spacing of the rows of beet-roots, the two extreme carriers 44 are shiftable on the shafts 45 and adapted to be held in the adjusted position by means of set screws 47.

The lowering and lifting of the shares and of the lifters is controlled from the driver's seat 5 by the rotation of a crank 48, which can be operated after a locking pawl 49 has been disengaged from a ratchet wheel 50. A shaft 51 is rotated by the crank 48, two winding drums 52 being fixed on said shaft and wire ropes 53 attached to said drums and to the shafts 45. When the crank 48 is turned, the carriers 44 with the shares 42 and the lifters 43 are simultaneously and uniformly raised or lowered.

The lifted out beet-roots are engaged at the end of the machine by a rake 54 arranged obliquely to the machine, along which the beet-roots roll in outward direction so that they are deposited at the end of the rake in rows. The rake 54 is pivotally and oscillatably connected by means of two bearings 55 to the rear wheel axle 6 and bears in the lowest position against two plates 56, so that it cannot penetrate into the ground. The rake 54 can be lifted by the operation of a hand lever 57 through the intermediary of a wire rope 58 or the like after a pawl 60 has been disengaged from a ratchet wheel 59.

I claim:-

1. A beet-root gathering machine, comprising in combination with the machine frame having a transverse beam, knives for

cutting the beet-root tops guided on said transverse beam independently of each other, slideable shoes controlling said cutting knives, guide rods to which said cutting knives and said shoes are connected, racks forming the ends of said guide rods, a sprocket wheel drive adapted to be operated from the driver's seat for raising and lowering said shoes and knives, conveying bands behind said shoes for conveying the cut off beet-root tops, conveying bands transversely arranged to the machine frame designed to receive the beet-root tops from said first mentioned conveying bands and for depositing at their ends the beet-root tops in heaps, shares for loosening the beet-roots, forkshaped lifters, longitudinal members on the machine frame on which said shares and lifters are fixed the one behind the other, transverse shafts to which said longitudinal members are connected, crank pins on which said transverse shafts are mounted, two winding drums for raising and lowering said crank pins, wire ropes connecting said winding drums to said transverse shafts, a rake at the end of the machine oblique to said machine, and means for connecting said rake oscillatably to the rear wheel axle.

2. A beet-root gathering machine as specified in claim 1, comprising in combination with the cutting knives controlled by slideable shoes and a conveying device having a bottom plate, oblique conveying devices behind said shoes, hinged plates connecting said oblique conveying devices with said bottom plate, a conveying device transverse to the machine frame, a box at the side of the machine for receiving the cut off beet-root tops from said transverse conveying device, a rotatable vane drum in said box, a spring controlled latch locking said drum, a pull rope for withdrawing said latch from the driver's seat, longitudinal members, shares for loosening the beet-roots, fork shaped lifters, said shares and forks fixed the one behind the other on said longitudinal members, transverse shafts to which said longitudinal members are connected, crank pins on which said transverse shafts are oscillatably mounted, winding drums for raising and lowering said longitudinal members, wire ropes attached to said shafts for lowering and raising said longitudinal members, and a rake obliquely attached to the end of the machine for depositing the beet-roots in rows.

In testimony whereof I affix my signature.
HEINRICH STÖLZE.
